UNITED STATES PATENT OFFICE.

DE WITT C. MEEKER AND WILLIAM A. BLACKMAN, OF CINCINNATI, OHIO.

SAFETY-GATE FOR HATCHWAY-DOORS.

SPECIFICATION forming part of Letters Patent No. 699,544, dated May 6, 1902.

Application filed October 1, 1900. Serial No. 31,624. (No model.)

To all whom it may concern:

Be it known that we, DE WITT C. MEEKER and WILLIAM A. BLACKMAN, citizens of the United States, residing at Cincinnati, in the 5 county of Hamilton, State of Ohio, have invented certain new and useful Improvements in Safety-Gates for Hatchway-Doors, of which the following is a full, clear, and exact description, reference being had to the accompanying drawings, forming part of this specification.

Our invention relates to that class of hatchway-doors which when closed lie parallel with and close to the floor or pavement, and more 15 particularly to cellar-doors of this description, which are usually of iron and lie close to and parallel with the sidewalk when closed; and it has for its object the application to such doors of a lazy-tongs gate which is permanently hinged to one of the doors on its under 20 side and is adapted to be folded up and fastened thereto when the doors are closed in such manner as to occupy but very little space and to be entirely out of the way, but when 25 the doors of the hatchway are opened upward can be unlatched, swung around, and drawn across the front edge of the hatchway and then have its free end secured to the opposite door, so as to form a secure safety-gate across 30 the front of the hatchway, all as will be hereinafter more fully set forth, and specifically pointed out in the claims.

In the accompanying drawings, Figure 1 is a perspective view of a hatchway, showing the 35 doors thereof opened and with our safety-gate applied and extending between the same. Fig. 2 is an enlarged inside elevation of the outer end of one of the doors, showing the safety-gate closed and secured thereto. Fig. 40 3 is an enlarged end elevation of the door to which the free end of the safety-gate is attached, showing parts of the same broken away and attached thereto.

The same letters of reference are used to 45 indicate identical parts in all the figures.

'A' is an ordinary hatchway, in this instance representing a cellar-opening, and having hinged to its sides a two-part door A² A³, as seen in Fig. 1, these two parts of the door 50 being held from falling outward when open by means of a chain, as shown, or they may

be supported in any other suitable or convenient manner. To one of the doors, in this instance A², is hinged, as at C, a bar A, in two parts, with an opening between them, 55 whose upper end fits over and is confined to an arm B, hinged, as at D, to the upper end of the door at its forward edge.

Pivoted to the upper part of the bar A in the opening between its two members is one 60 end of a lazy-tongs gate A⁴, the opposite member of the same end of the gate being secured between the two parts of the bar A, so as to have sliding motion thereon by means of pins, as at E. The opposite end of the lazy-tongs 65 gate has its one member F perforated to receive a pin M, which is passed through a lug on the inner side of the door A³, while the other member G has its lower end shaped to engage a lug K on the door A³. 70

It results from the foregoing construction that when it is desired to close the hatchway-doors the free end of the lazy-tongs gate is disconnected from the door A³, and the gate is closed up upon itself and swung around to 75 the position shown in Fig. 2, the bar A sliding upon the bar B to permit bar A to come parallel with the front edge of the door A², and any suitable fastening, such as a pivoted button L, is turned over the end of the gate 80 to secure it to the under side of the door.

When the doors are opened, it is only necessary to turn the button L, swing the gate A⁴ around, and draw it across the front of the hatchway, where its free ends can be secured 85 to the door A³, as will be readily understood.

It is to be observed that with the doors slanting outward when open it is necessary that the upper hinge for the lazy-tongs gate should have an extensible member or sliding 90 connection, such as provided for by the arm B; otherwise the gate could not be made to occupy a position parallel with the floor or sidewalk.

Having thus fully described our invention, 95 we claim—

1. In a door-guard, a hinge attached to the door, a folding gate pivoted to the said hinge, and means for engaging the free end of the gate when extended. 100

2. In a door-guard, a hinge attached to a cellar-door, a folding gate pivoted to said

hinge, and a catch fixed to said cellar-door adapted to engage the outer end of the gate when collapsed and folding inwardly against the door.

5 3. In combination with a two-leaved door, a lazy-tongs safety-gate hinged to the under side of one of the said leaves, and fastenings upon the other leaf to which the free ends of the lazy-tongs may be secured when the door is 10 in its open position, substantially as described.

4. In combination with a two-leaved hatchway-door, a lazy-tongs gate hinged to the under side of one of the said leaves by means of a permanent hinge and an extensible hinge, 15 and fastenings upon the other leaf to which the free ends of the lazy-tongs may be secured

when the door is in its open position, substantially as described.

5. The herein-described safety-gate construction for hatchway-doors, comprising the 20 hinged doors, A², A³, lazy-tongs gate, A⁴, hinged to the door A², by means of the stationary hinge C and extensible hinged joint B, and opposite fastenings, as M, K, on the door A³, for the free ends of the gate, sub- 25 stantially as described.

DE WITT C. MEEKER.
WILLIAM A. BLACKMAN.
